No. 700,064.

Patented May 13, 1902.

A. J. MARKHAM.
STEAM ENGINE.

(Application filed Feb. 8, 1902.)

(No Model.)

UNITED STATES PATENT OFFICE.

ANDREW J. MARKHAM, OF ELBA, NEBRASKA, ASSIGNOR OF ONE-HALF
TO JOHN MORROW, OF ELBA, NEBRASKA.

STEAM-ENGINE.

SPECIFICATION forming part of Letters Patent No. 700,064, dated May 13, 1902.

Application filed February 8, 1902. Serial No. 93,191. (No model.)

To all whom it may concern:

Be it known that I, ANDREW J. MARKHAM, a citizen of the United States, residing at Elba, in the county of Howard and State of Nebraska, have invented a new and useful Steam-Engine, of which the following is a specification.

My invention relates to certain improvements in steam-engines, and has for its principal object to provide the cylinder with valves and valve-operating mechanism so arranged as to effect the simultaneous opening and closing of the steam inlet and exhaust valves at opposite sides of the cylinder at the end of the stroke of the piston.

A further object of the invention is to provide for the adjustment of the parts to enable the valves to be opened or closed at any desired point near the end of the stroke, as fully set forth hereinafter.

With these and other objects in view the invention consists in the novel construction and combination of parts hereinafter described, illustrated in the accompanying drawings, and particularly pointed out in the appended claims.

In the drawings, Figure 1 is a sectional plan view illustrating the cylinder, valve, and valve-operating mechanism of an engine made in accordance with my invention. Fig. 2 is a side elevation of the same.

In the cylinder 5 is a piston 6, which may be of any ordinary construction, said piston being connected by a piston-rod 7 to a connecting-rod 8, either to a crank-shaft or other point where the pressure of the steam is to be utilized or converted into motion. On opposite sides of the cylinder are steam-chests 9 and 10, respectively, the cylinder being connected to said steam-chests by inlet-ports 11 and exhaust-ports 12. To the steam-chest 9 is connected a supply-pipe 14, and to the steam-chest 10 is connected an exhaust-pipe 15, or the latter may be in the form of a simple opening to exhaust the steam or other fluid directly to the outer air.

In the steam-chest 9 is a slide-valve 16, having a port 17, which may be moved to place either of the cylinder-ports in communication with the steam-supply, and said valve is con-

nected to a valve-stem 18, leading out through a stuffing-box 19 of the usual character. In the exhaust-chest is a valve 20, having port 21, which may be moved into alinement with either of the cylinder-ports 12 to permit the escape of steam from either end of the cylinder. The valve 20 is connected to a valve-stem 22, extending out through a stuffing-box 23.

The engine is provided with cross-head guides 24 of any ordinary type and adapted for the reception of a suitable cross-head 25, to which are connected the piston-rod 7 and the connecting-rod 8. At a point near the forward end of the cross-head guides is bolted a transverse bar 26, to which is centrally pivoted a locking-bar 27, having at its opposite ends pins or bolts 28, to which are connected the ends of the valve-rods 18 and 23. The valve-rods 18 and 23 are preferably sectional, the adjacent ends of the sections being threaded for the reception of a nut 29, having right and left hand screw-threads for engagement with the similar threads of the sections of the valve-stem, so that the position of the valve may be properly adjusted at any time by increasing or decreasing the distance between the center of its port and the pin or bolt 28.

To the cross-head is secured a tappet-bar 30, which projects beyond the line of the cross-head and is disposed immediately above the valve-rod 18, said valve-rod for the greater portion of its length being substantially rectangular in form and provided with projecting lugs 31 for engagement by the cross-head bar 30 as the latter is traveled to and fro by the movement of the piston. The distance between the lugs 31 with respect to the stroke of the piston is such that as the latter nears the limit of its stroke in either direction the tappet-bar will engage with one or other of the lugs, moving the valve-rod 18 and the steam-valve to the opposite position for the admission of steam to the opposite ends of the cylinder. This movement is transmitted by the connecting-bar 27 to the valve-rod 22 of the exhaust-valve in reverse direction, the operation being such that as the steam-port leading from one end of the cylinder is open the above port leading to the opposite end of

the cylinder will also be open, permitting the free escape of the steam from the exhaust side of the piston.

In order to provide for the adjustment of the valve movement with respect to the stroke of the piston, I preferably provide the lugs 31 with threaded openings for the reception of adjustable bolts 32, which may be moved either toward or from each other, as circumstances may require, to permit the movement of the valve at a desired point in the stroke of the piston. These bolts will also serve to prevent any wear on the lugs and may be adjusted from time to time in order to compensate for wear either on the tappet-bar or on the ends of the bars with which said tappet-bar makes contact.

While the construction herein described, and illustrated in the accompanying drawings, is the preferred form of the device, it is obvious that various changes in the size, proportion, and minor details of the structure may be made without departing from the spirit or sacrificing any of the advantages of my invention.

Having thus described my invention, what I claim is—

1. The combination in a steam-engine, of the cylinder, valve-chests arranged on opposite sides of the same, there being ports or passages leading from the opposite ends of the cylinder to said valve-chests, slide-valves disposed within the chest, valve-rods connected to said valve and to each other, one of said valve-rods having a pair of lugs, and a tappet-bar actuated by the movement of the piston of the engine and adapted to make contact with said lugs.

2. The combination in an engine, of the

cylinder, valve-chests arranged on opposite sides of the same, there being ports or passages leading between the valve-chests and the opposite ends of the cylinder, a piston in said cylinder, a piston-rod connected to the piston, a tappet-bar connected to and movable with the piston-rod, valve-rods connected to the valves, a pivoted lever to which both rods are connected, and one of said valve-rods being provided with lugs adapted to be engaged by the tappet-bar, substantially as specified.

3. The combination in a steam-engine, of the cylinder, valve-chests arranged on opposite sides of the same, there being ports or passages leading between the valve-chests and the opposite ends of the cylinder, a piston in said cylinder, a piston-rod 7 connected to the piston, a cross-head 25 connected to the piston-rod, cross-head guides 24 carrying said cross-heads, a tappet-bar 30 secured to the cross-head and projecting laterally therefrom, a transverse bar 26 connecting the cross-head guides, a bar 27 pivotally connected to said bar 26, an adjustable valve-rod 22 connecting the exhaust-valve to one end of the bar 27, an adjustable valve-rod 18 connecting the steam-inlet valve to said bar 27, lugs 31 carried by said valve-rod 18, and screw-bolts 32 carried by said lugs and adapted for contact with said tappet-bar 30, substantially as and for the purpose specified.

In testimony that I claim the foregoing as my own I have hereto affixed my signature in the presence of two witnesses.

ANDREW J. MARKHAM.

Witnesses:

PETER JEPSON,
JOHN MORROW.
